UNITED STATES PATENT OFFICE

JOSÉ B. BARREDO, OF LOS ANGELES, CALIFORNIA

MUSICAL STRING INSTRUMENT

Application filed June 26, 1931. Serial No. 547,092.

This invention relates to musical string instruments and has for the primary object, the provision of a device of the above stated character which will be convenient and easy to play and will produce musical tones which are mellow and sweet and is capable of permitting any character of music to be played thereon.

- Another object of this invention is the provision of a musical string instrument of the above stated character which will be simple, durable and efficient and which may be manufactured and sold at a comparatively low cost.
- With these and other objects in view, this invention consists in certain novel features of construction, combination and arrangement of parts to be hereinafter more fully described and claimed.
- For a complete understanding of my invention, reference is to be had to the following description and accompanying drawing, in which

Figure 1 is a side elevation partly in section illustrating a musical string instrument constructed in accordance with my invention.

Figure 2 is a fragmentary vertical section illustrating the means of mounting and adjusting one end of the string.

Figure 3 is a fragmentary front elevation illustrating the same.

Figure 4 is a fragmentary front elevation illustrating the mounting of the string bridge to the body of the instrument.

Figure 5 is a fragmentary sectional view illustrating the means of attaching the other end of the string to the body of the instrument.

Referring in detail to the drawing, the numeral 1 indicates a metallic cylindrical and elongated body. The body 1 may be made of aluminum or any other metal suitable for the purpose and is of semi-hollow formation, the upper end of the body being of solid formation as shown in Figure 1 and has secured thereto a head 2 of tubular construction and including a series of angularly related portions to provide the head of an artistic appearance. The lower end of the body is received within a tubular sound box

3 which includes a plurality of angularly related portions and one of said portions is provided with oppositely disposed openings 4 and 4' through which a string 5 may be passed. An anchoring element 6 of tapered formation is secured to the end of the string and positioned within one of the openings 4 and is provided with a flange portion 7 to engage the outer wall of the sound box 3.

A circular bridge 8 is secured within a groove or seat formed in the body 1 by rivets or other suitable fasteners and is provided with a peripheral groove 9' to receive the string 5. The string 5 after passing over the bridge 8 is trained over a second bridge 9 of circular formation and provided with a peripheral groove and is journaled in a slot 10 of the head 2. The head 2 is provided with a tone regulator 11 adjacent to the bridge 9 and has the string 5 secured thereto and is adapted to wind a portion of said string thereon for the purpose of tuning or tensioning the string as desired.

The free end of the sound box 3 has a funnel shaped element 12 secured thereto for the purpose of permitting the sound within the sound box to easily escape with a soft and mellow tone. The sounds or tones of the string are delivered into the sound box by the end of the string anchored within said tone box due to the string passing through the opening 4 without contacting with the walls thereof and also by the bridge 8.

A hook shaped rest 13 is secured to the sound box 3 and is adapted to rest on the floor or a support while the upper end of the body 1 is positioned against the shoulder of the player, thus the instrument is supported in an inclined position so that the bow held in one hand of the player may be moved across the string 5 in the proper manner to produce musical tones. The musician grips the string 5 along the upper end of the body with the thumb and fingers of the other hand for the purpose of changing the tones of the string.

The string 5 may be of any well known type and preferably made from guts or hairs of horses' tails.

While I have shown and described the preferred embodiment of my invention, it will be

understood that minor changes in construction, combination and arrangement of parts may be made without departing from the spirit and scope of my invention, as claimed.

Having thus described my invention, what I claim is:

A musical string instrument comprising an elongated tubular body forming a portion of a sound box, a head of hollow formation secured to one end of the body, a musical string adjustably secured to the head, a tubular element connected to the other end of the body and cooperating with the latter to form a complete sound box, said element including angularly related portions and one of said portions disposed at substantially right angles to the body and provided with oppositely disposed openings to receive the string and permit the latter to enter the sound box and to extend substantially parallel with the body, a string securing means having the string secured thereto and mounted in one of the openings of the sound box with a string extending across said sound box, and a bridge between the string and the body.

In testimony whereof I affix my signature.

JOSÉ B. BARREDO.
